UNITED STATES PATENT OFFICE.

HUGH W. SANFORD, OF KNOXVILLE, TENNESSEE.

MINE CAR.

Application filed June 23, 1924. Serial No. 721,837.

To all whom it may concern:

Be it known that I, HUGH W. SANFORD, a citizen of the United States, residing at Knoxville, in the county of Knox and State of Tennessee, have invented a new and useful Improvement in Mine Cars, of which the following is a specification, reference being had to the accompanying drawing.

My invention relates particularly to mine cars having a metal frame and a metal bottom.

The object of this invention is to produce a mine car in which the end structure of the frame includes an extension of the metal bottom plate, the end structure comprising coupling elements and bumper elements.

In the accompanying drawings,

Fig. 1 is a plan of a mine car frame end structure embodying my improvement; 20 Fig. 2 is an elevation of the same end structure;

Fig. 3 is a side elevation of the same structure looking at the structure of Figs. 1 and 2 from the left;

Fig. 4 is an upright section on the line, 4—4, of Fig. 1, looking toward the right, said line being in the middle longitudinal plane of the car frame;

Fig. 5 is an upright section on the line, 5—5, of Fig. 1, looking toward the right;

Fig. 6 is a horizontal section on the line, 6—6, of Fig. 2;

Fig. 7 is an upright section on the line, 7—7, of Figs. 1 and 2, looking toward the right;

Fig. 8 is an upright, transverse section on the line, 8—8, of Fig. 1, looking in the direction of the arrow;

Fig. 9 is a perspective of one of the corner members used for joining the end structure to the side sills;

Fig. 10 is a perspective of an anchor plate located at the middle of the end structure;

Fig. 11 is a plan showing a sheet steel blank from which a part of the frame end structure is formed;

Fig. 12 is a perspective of the main part of the end structure, the corner members and some other parts being omitted;

Fig. 13 is a horizontal section on the line, 13—13, of Fig. 2;

Fig. 14 is a perspective of the end structure bumper member;

Fig. 15 is a horizontal section on the line, 15—15, of Fig. 2;

Fig. 16 is a view similar to Fig. 4, the end structure being modified;

Fig. 17 is a section similar to Fig. 5, but showing the form of Fig. 16;

Fig. 18 is a perspective similar to Fig. 12, the form of the structure being the same as in Figs. 16 and 17;

Fig. 19 is a view similar to Fig. 16, the end structure being in another form;

Fig. 20 is a perspective similar to Figs. 12 and 17, the main elements of the end structure being those of Fig. 19;

Fig. 21 is a section similar to Fig. 19, and illustrates still another form;

Fig. 22 is a perspective similar to Figs. 7 and 18, and illustrates the main elements of the main structure of Fig. 21;

Fig. 23 is a section similar to Figs. 19 and 21 but illustrates a different form;

Fig. 24 is a perspective showing the main elements of the form of Fig. 23;

Figs. 25 and 26 in the same manner illustrate yet another form;

Figs. 27 and 28 in the same manner illustrate yet another form.

Referring first to Figs. 1 to 15, inclusive, of the drawings, A, A are the side sills. In the form shown in the drawings these sills are of structural channel-shape with flanges, A¹, directed outward. The frame end structure is applied to the ends of these sills.

A blank plate, B, (Fig. 11) is bent on the dotted lines, B¹, to form an upright inner or back wall, B², an upper outward-directed narrow flange, B³, and a lower horizontal outward-directed flange, B⁴, wider than the flange, B³, and having its outer corners cut to form oblique edges, B⁵.

This plate, B, is long enough to make the back wall, B², partially over-lap the ends of the end sills, A, A. Said back wall and the side sills are joined to each other by means of the corner angle members, C, one of these angle members is shown in perspective in Fig. 9. One arm or blade of the angle member rests against the outer flat face of the back member, B², and is secured to the

- member, B^3 , by bolts or rivets, C^1 , extending through said blade and the wall, B^2 . The drawings show six such bolts or rivets. The other arm or blade of the angle member extends into the space between the flanges, A^1 , of the adjacent side sill and bears against the upright web of the side sill. Bolts or rivets, C^2 , extend through said blade and said web to join said parts to each other.
- 10 In the form shown in the drawings, six such bolts or rivets, C^2 , are used. These corner angle members and the bolts or rivets used for securing these angle members to the wall, B^2 , and the side sills, A , are to be sufficiently strong to give rigidity to the frame. The wall, B^2 , is preferably made wider than the height of the side sills, A , to allow making a coupling link space as will be described further on.
- 20 The metal bottom plate, D , is extended horizontally across the flange, B^3 , to form the end structure member, D^1 , of substantially the same dimensions and shape as the lower flange, B^4 , and having oblique edges, D^2 , corresponding to the oblique edges, B^5 , of the flange, B^4 . The member, D^1 , is secured to the flange, B^3 , by bolts or rivets, D^3 , extending through the member, D^1 , and the flange, B^3 . An inner or filling member, E , of strong wood, preferably oak, is placed on the lower flange, B^4 , and against the upright wall, B^2 , of the plate member, B . The upper and the lower and the inner face of the wood filling member, E , are straight; while the outward face of the wood member nearly conforms to the outer edges of the lower flange, B^4 , and the upper flange, D^1 , which, as above described, is an extension or continuation of the bottom, D , the wood member being extended outward a little beyond said flanges.
- 45 Midway between the ends of the upright wall, B^2 , an angle form anchor plate, F , extends across the upper face of the wood member, E , and between said member and the upright wall, B^2 , and is secured to said wall by rivets, F^1 (Figs. 4, 10, 13 and 15).
- 50 The horizontal part of the anchor member has a hole, F^2 , to receive the coupling bolt to be described further on. A bumper member, G , is curved and of channel-form, having an upright web, G^1 , and an upper flange, G^2 , and a lower flange, G^3 . Said bumper member is placed at the middle of the end structure and has its web, G^1 , bearing against the outer, upright face of the wood filling member, E , while its upper flange, G^2 , rests on the upper face of said wood filling member, E , and its lower flange, G^3 , extends across the lower face of the flange, B^4 , of the plate member, D . This bumper member is to receive contact or impact from the bumper of another car. The bumper

member and the outer part of the wood member form a bumper, the wood being a cushioning member or material against which the bumper member rests.

Thus a coupling link space is left between the upper face of the wood member, E , and the flange, D^1 , which, as above described, is a continuation of the bottom, D . Upright binding bolts, H , extend through the bumper member and the flange, B^4 , and the wood member, E , and the upper flange, E^1 . Between the bumper member and the upper flange, D^1 , each of said bolts is surrounded by a spacing sleeve, H^1 , whereby the distance between the bumper member and the flange, D^1 , is maintained. Between the bolts, H , and on the middle, longitudinal line of the car, is the upright coupling bolt, I , extending through the two flanges of the bumper member and through the wood member and the hole, F^2 , in the horizontal part of the anchor plate, F , and through the upper flange, D^1 , and the lower flange, B^4 . Between the upper flange, D^1 , and the upper flange, G^2 , of the bumper member, the coupling bolt, I , is surrounded by a spacing sleeve, I^1 , which maintains the distance between said flanges. A coupling link, (not shown) surrounds the bolt, I , and the spacing sleeve, I^1 .

Between the bumper member, G , and the ends of the end structure, bolts, J , extend through the lower flange, B^4 , and the wood filling member, E , and the upper flange, D^1 . Between the wood member and the web, D^1 , each of said bolts is surrounded by a spacing sleeve, J^1 , and between each such spacing sleeve and the wood filling is a washer, J^2 .

By means of the various bolts and spacing sleeves and washers, the several members are firmly bound to each other to form the composite frame end structure.

It is to be observed that this composite frame end structure includes a bumper and a draw bar structure, the upper flange, D^1 , and the lower flange, B^4 , and the anchor plate, F , performing draw-bar function.

The remaining figures of the drawings show variations of the frame and structure already described.

In Figs. 16, 17 and 18, the upper flange, B^3 , and the upper part of the upright back wall, B^2 , are omitted. The bottom plate extension is bent to form an upright web or wall, D^4 , which over-laps the rear face of the wall, B^2 . The walls, B^2 and D^4 , are joined to each other by horizontal rivets, C^1 , which also join the corner members, C , to the wall, D^4 . The bottom plate is extended outward from the upper part of the wall, D^4 , to make the flange, D^1 , the same as in Figs. 3, 4, 7 and 12. The anchor plate, F , is applied as in Figs. 4 and 15, the rivets, F^1 , extending through the anchor plate and the walls, B^2 and D^4 .

In Figs. 19 and 20, the parts are the same as in Figs. 16, 17 and 18, excepting that the anchor plate is omitted and an anchor flange, F^3 , is extended horizontally outward from the upper edge of the wall, B^2 , said flange conforming in size and shape to the flanges, D^1 and B^1 , of Figs. 12 and 18.

In Figs. 21 and 22, the bottom plate, D , is extended forward or outward to form a lower end structure flange, K , similar to the lower flange, B^4 , of Fig. 12, the flange, K , having the oblique edges, K^1 . Then on this flange, K , is placed a metal plate member similar to the member, B , of Fig. 12, but inverted to comprise the upright back wall, K^2 , the upper forward directed flange, K^3 , and the relatively narrow lower forward-directed flange, K^4 , secured to the lower flange, K , by rivets or bolts, K^5 . In Figs. 23 and 24, the parts are the same as in Figs. 21 and 22, excepting that the flange, K^4 , of Figs. 21 and 22 is omitted and a flange, K^6 , is turned rearward or inward along the lower edge of the upright wall, K^2 , and made to rest on the main part of the metal plate bottom, D , immediately at the rear of the flange, K , and secured thereto by bolts or rivets, K^7 .

In the form shown by Figs. 21 and 22, and in the form shown by Figs. 23 and 24, the floor plate is off-set adjacent the lower edge of the upright wall, K^2 . This serves to give greater firmness to the structure. In the forms shown by Figs. 25 and 26, the member having the upright wall, K^2 , and the upper flange, K^3 , and the relatively narrow flange, K^4 , is again present as in Figs. 21 and 22, and said lower flange rests on the bottom, D , the bottom being extended only as far as the outer edge of the flange, K^4 . A flange plate, L , similar to the flange, B^4 , in Fig. 12, extends under the part of the bottom, D , on which the flange, K^4 , rests. Upright rivets, L^1 , extend through the flange, K^4 , the extended part of the body, D , and the flange plate, L , and join those parts to each other. The three parts thus overlapped and joined by rivets add strength to this end structure.

In the form shown by Figs. 27 and 28, the metal plate bottom, D , is extended forward at approximately the same height as in Figs. 3, 4 and 7; but this extended part of the bottom is made a middle end structure flange, M , similar to the flange, F^3 , of Figs. 19 and 20. From a lower flange, M^1 , similar to the flange, B^4 , of Fig. 12 rises a back wall, M^2 , extending upward to the flange, M . From the upper part of the wall, M^2 , a flange, M^3 , extends horizontally inward away from the wall, M^2 , along the lower face of the extended part of the bottom, D . Another plate member which is like the plate member, M^1 , M^2 , M^3 , but reversed and composed of the flange, M^4 , the

upright wall, M^5 , and the inner flange, M^6 , corresponding, respectively, to the flange, M^1 , the wall, M^2 , and the flange, M^3 , is placed above the flange, M^1 , with its inner flange, M^6 , resting on the flange, M^1 , directly above the flange, M^3 . Bolts or rivets, M^7 , extend through the flange, M^6 , the extension of the bottom, D , and the flange, M^3 , and bind those parts together. The corner members, C , are joined to the wall, M^2 .

Over-lapping the metal plate members in these various forms of the end structure and joining them by rivets adds strength to the structure, particularly to resist horizontal strains applied parallel to the length of the car.

In the several forms beginning with the form of Figs. 16 and 17, the wood filling member, E , and the bumper member, G , and the bolts and other auxiliary members may be applied as described in connection with the form of Figs. 1 to 15, inclusive, excepting that in the form of Figs. 19 and 20 and in the form of Figs. 27 and 28, the anchor plate, F , is omitted and the flanges, F^3 , and M substituted.

The wood filling member adds to the strength of the end structure and serves as a cushion to absorb shock.

I claim as my invention,

1. In a railway car, the combination with side sills and a plate metal bottom, of a frame end structure joined to the side sills and formed in part of an extension of the bottom and another member joined to said extension, the extension reaching outward beyond its junction with said other member, substantially as described.

2. In a railway car, the combination with side sills and a plate metal bottom, of a frame end structure joined to the side sills and formed in part of an extension of the bottom reaching from side sill to side sill, and another member joined to said extension, the extension reaching outward beyond its junction with said other member, substantially as described.

3. In a railway car, the combination with side sills and a plate metal bottom, of a frame end structure joined to the side sills and formed in part of an extension of the bottom reaching from side sill to side sill, and another member also reaching from side sill to side sill and joined to said extension, the extension reaching outward beyond its junction with said other member, substantially as described.

4. In a railway car, the combination with side sills and a plate metal bottom, of a frame end structure joined to the side sills and formed in part of an extension of the bottom and another member also reaching from side sill to side sill and joined to said extension, said extension being in a plane at an elevation different from the plane of

- the bottom and reaching outward beyond the upper part of said other member, substantially as described.
5. In a railway car, the combination with 5 side sills, of a plate metal bottom extending outward in the direction of the length of the car, beyond the ends of the side sills, and another member combined with the extended part of the bottom to form an end 10 structure, said extension forming a draw-bar element, substantially as described.
6. In a railway car, the combination with 15 side sills, of a plate metal bottom extended outward in the direction of the length of the car, beyond the ends of the side sills, and another member combined with the extended part of the bottom to form a frame 20 end structure, said extension and said other member forming draw-bar elements, substantially as described.
7. In a railway car, the combination with 25 side sills, of a plate metal bottom extended, in the direction of the length of the car, beyond the ends of the side sills, and another member reaching from side sill to side sill and combined with the extended part of the bottom to form a frame end structure, said extension and said other member forming draw-bar elements, substantially as described.
8. In a railway car, the combination with 35 side sills, of a plate metal bottom extending outward in the direction of the length of the car, and another member joined to the extended part of the bottom to form a frame end structure, the extension of the bottom reaching outward beyond the junction of the extension and the other member and said extension forming a draw-bar element, substantially as described.
9. In a railway car, the combination with 45 side sills, of a plate metal bottom extending outward in the direction of the length of the car, and another member joined to the extended part of the bottom to form a frame end structure, the extension of the bottom reaching outward beyond the junction of the extension and the other member and said extension and said other member forming draw-bar elements, substantially as described.
10. In a railway car, the combination with 55 side sills, of a plate metal bottom extended outward, in the direction of the length of the car, beyond the ends of the side sills, and another member combined with the extended part of the bottom to form a frame end structure, the extended part of the bottom reaching outward beyond its junction with the other member, and corner pieces joining the end structure to the side sills, substantially as described.
11. In a railway car, the combination with 65 side sills and a plate metal bottom, of a frame end structure formed in part of an extension of the bottom, and another member joined to said extension, the extension reaching outward beyond the junction with said other member, and corner pieces joining the end structure to the side sills, substantially as described.
12. In a railway car, the combination with 70 side sills and a plate metal bottom, of a frame end structure formed in part of an extension of the bottom reaching from side 75 sill to side sill, and another member joined to said extension, the extension reaching outward beyond the junction with said other member, and corner pieces joining the end structure to the side sills, substantially as described.
13. In a railway car, the combination with 80 side sills, of a plate metal bottom extended outward, in the direction of the length of the car, beyond the ends of the side sills, and another member located below and combined with the extended part of the bottom to form a frame end structure, said extension reaching beyond its junction with the other member, substantially as described.
14. In a railway car, the combination with 85 side sills, of a plate metal bottom extended outward, in the direction of the length of the car, beyond the ends of said sills and in a plane different from the plane of the bottom, and another member combined with the extended part of the bottom to form a frame end structure, said extension reaching beyond its junction with the other member, substantially as described.
15. In a railway car, the combination with 90 side sills, of a plate metal bottom at approximately the level of the lower parts of said sills and extended outward, in the direction of the length of the bar, beyond the 95 ends of said sills and in a plane different from the plane of the bottom, and another member combined with the extended part of the bottom to form a frame end structure, said extension reaching beyond its junction with the other member, substantially as described.
16. In a railway car, the combination with 100 side sills, of a plate metal bottom extended outward, in the direction of the length of the car, beyond the ends of said sills and in a plane different from the plane of the bottom, another member combined with the extended part of the bottom to form a frame end structure, said extension reaching beyond its junction with the other member, and corner pieces connecting the end structure to the side sills, substantially as described.
17. In a railway car, the combination with 105 side sills, of a plate metal bottom at approximately the level of the lower parts of said sills and extended outward, in the direction of the length of the car, beyond the 110 ends of said sills and in a plane different from the plane of the bottom, and another member combined with the extended part of the bottom to form a frame end structure, said extension reaching beyond its junction with the other member, and corner pieces connecting the end structure to the side sills, substantially as described.

from the plane of the bottom, another member combined with the extended part of the bottom to form a frame end structure, said extension reaching beyond its junction with

5 the other member, and corner pieces connecting the end structure to the side sills, substantially as described.

18. In a railway car, the combination with side sills, of a plate metal bottom at approximately the level of the lower parts of 10 said sills and extended outward and upward in the direction of the length of the car, beyond the ends of said sills, and another member combined with the extended part 15 of the bottom to form a frame end structure, said extension reaching beyond its junction with the other member, substantially as described.

19. In a railway car, the combination with 20 side sills, of a plate metal bottom at approximately the level of the lower parts of said sills and extended outward and upward in the direction of the length of the car, beyond the ends of said sills, another member combined with the extended part of 25 the bottom to form a frame end structure, said extension reaching beyond its junction with the other member, and corner pieces connecting the end structure to the side sills, 30 substantially as described.

20. In a railway car, the combination with side sills, of a plate metal bottom at approximately the level of the lower parts of 35 said sills and extended outward, in the direction of the length of the car, beyond the ends of said sills, and another member placed below and combined with the extended part of the bottom to form a frame end structure, 40 said extension reaching beyond its junction with the other member, substantially as described.

21. In a railway car, the combination with side sills, of a plate metal bottom at approximately the level of the lower parts of 45 said sills and extended outward, in the direction of the length of the car, beyond the ends of said sills, and another member combined with the extended part of the bottom to form a frame end structure, said extension constituting a draw-bar element, substantially as described.

22. In a railway car, the combination with side sills, of a plate metal bottom at approximately the level of the lower parts 50 of said sills and extended upward and outward, in the direction of the length of the car, beyond the ends of said sills, and another member combined with the extended part of the bottom to form a frame end structure, said extension constituting a draw-bar element, substantially as described.

23. In a railway car, the combination with side sills, of a plate metal bottom extended outward, beyond the ends of said sills, and another plate member combined with and

overlapping and riveted to the extended part of the bottom and spaced from the end edge of said extension to form a frame end structure, substantially as described.

24. In a railway car, the combination with 70 side sills, of a plate metal bottom at approximately the level of the lower parts of said sills and extended outward, in the direction of the length of the car, beyond the ends of said sills, and another plate member bearing against the lower face of a horizontal part of the bottom extension and riveted thereto to form an end frame structure, said extension reaching beyond its junction with the other member, substantially 75 as described.

25. In a railway car, the combination with side sills, of a plate metal bottom extended 80 outward, in the direction of the length of the car, beyond the ends of the sills and forming a draw-bar member, substantially as described.

26. In a railway car, the combination with side sills, of a plate metal bottom extended 90 outward, in the direction of the length of the car, beyond the ends of the sills and forming a draw-bar member, and another draw-bar member adjacent said extension, substantially as described.

27. In a railway car, the combination with 95 side sills, of a plate metal bottom extended outward, in the direction of the length of the car, beyond the ends of the sills and forming a draw-bar member, another draw-bar member adjacent said extension, and 100 said two draw-bar members being apertured to receive a coupling bolt and said draw-bar members being spaced from each other to receive a coupling link, substantially as described.

28. In a railway car, the combination with side sills, of a plate metal bottom extended 105 outward, in the direction of the length of the car, beyond the ends of the side sills, and another metal plate member joined to the bottom extension, said extension and said other plate member being apertured to receive a coupling bolt, substantially as described.

29. A composite end frame structure for 110 railway cars, said structure comprising a plate metal bottom extended outward, in the direction of the length of the car, another metal plate member combined with the extended part of the bottom, said extension 120 reaching beyond its junction with the other member, and a filling member located between said extension and said other plate member, substantially as described.

30. A composite end frame structure for 125 railway cars, said structure comprising a plate metal bottom extended outward, in the direction of the length of the car, another plate metal combined with the extended part of the bottom, said extension 130

reaching beyond its junction with the other member, and a filling member located between and reaching outward beyond said extension and said other plate member, substantially as described.

31. A composite end frame structure for railway cars, said structure comprising a plate metal bottom extended outward, in the direction of the length of the car, another plate member combined with the extended part of the bottom, said extension reaching beyond its junction with the other member, and a wood filling member between said extension and said other plate member, substantially as described.

32. A composite end frame structure for railway cars, said structure comprising a plate metal bottom extended outward, in the direction of the length of the car, another plate member combined with said extension, said extension reaching beyond its junction with the other member, and corner pieces connecting the extension and the side sills, substantially as described.

33. A composite end frame structure for railway cars, said structure comprising a plate metal bottom extended outward, in the direction of the length of the car, another plate member combined with said extension, said extension presenting an upright face, said extension reaching beyond its junction with the other member, and angle-form corner pieces secured to said face and the sides of the side sills, substantially as described.

34. A composite end frame structure for railway cars, said structure comprising a plate metal bottom extended outward, in the direction of the length of the car, another plate member combined with said extension one of said plate members presenting an upright face adapted to have corner pieces attached thereto, said extension reaching beyond its junction with the other member, and a filling member placed between said extension and said other plate member, substantially as described.

35. A composite end frame structure for railway cars, said structure comprising a plate metal bottom extended outward, in the direction of the length of the car, another plate member riveted to said extension, and said extension presenting an upright face, and corner pieces attached to said face and the end sills, substantially as described.

36. A composite end frame structure for railway cars, said structure comprising a plate metal bottom extended outward, in the direction of the length of the car, another plate member combined with the extended part of the bottom, said extension reaching beyond its junction with the other member, a filling member between said extension and said other plate metal mem-

ber, and a metal bumper member extending across the filling member, substantially as described.

37. A composite end frame structure for railway cars, said structure comprising a plate metal bottom extended outward, in the direction of the length of the car, another plate member combined with the extended part of the bottom, a filling member between said extension and said other plate metal member, a metal bumper member extending across the filling member, and a coupling bolt extending through said plate members and said filling member, substantially as described.

38. A composite end frame structure for railway cars, said structure comprising a plate metal bottom extended outward, in the direction of the length of the car, another plate member combined with the extended part of the bottom, a filling member between said extension and said other plate metal member, a metal bumper member extending across the filling member, and a coupling bolt extending through said plate members and said filling member and said metal bumper member, substantially as described.

39. A composite end frame structure for railway cars, said structure comprising a plate metal bottom extended outward, in the direction of the length of the car, another plate metal member combined with the extended part of the bottom, said extension reaching beyond its junction with the other member, and a filling member of cushioning material located between said extension and said other plate member, substantially as described.

40. A composite end frame structure for railway cars, said structure comprising a plate metal bottom extended outward, in the direction of the length of the car, another plate metal member combined with the extended part of the bottom, and an anchor member between said plate members, substantially as described.

41. A composite end frame structure for railway cars, said structure comprising a plate metal bottom extended outward, in the direction of the length of the car, another plate metal member combined with the extended part of the bottom, an anchor member between said plate members, and a filling member located between the anchor member and the lower of the plate metal members, substantially as described.

42. A composite end frame structure for railway cars, said structure comprising a plate metal bottom extended outward, in the direction of the length of the car, another plate metal member combined with the extended part of the bottom, an anchor member located between said plate metal members, and a flanged bumper member having

one flange over-lapping a part of the anchor member, substantially as described.

43. A composite end frame structure for railway cars, said structure comprising a plate metal bottom extended outward, in the direction of the length of the car, another plate metal member combined with the extended part of the bottom, a filling member resting on the lower plate metal member, an anchor plate extending across a part of the filling member, and a flanged bumper member having one flange over-lapping a part of the anchor member and a part of the lower plate metal member, substantially as described.

44. A composite end frame structure for railway cars, said structure comprising a plate metal bottom extended outward, in the direction of the length of the car, another plate metal member combined with the extended part of the bottom, an anchor member located between said plate metal members, a flanged bumper member having one flange over-lapping a part of the anchor member, and a coupling bolt extending through the other members, substantially as described.

45. A composite end frame structure for railway cars, said structure comprising a plate metal bottom extended outward, in the direction of the length of the car, another plate metal member combined with the extended part of the bottom, a filling member resting on the lower plate metal member, an anchor member extending across a part of

the filling member, a flanged bumper member having one flange over-lapping a part of the anchor member and a part of the lower plate metal member, and a coupling bolt extending through the other members, substantially as described.

46. A composite end frame structure for railway cars, said structure comprising a plate metal bottom extended outward, in the direction of the length of the car, another plate metal member combined with the extended part of the bottom, a filling member located between said extension and said other plate member, a bolt extending through said plate members and said filling member, and a spacing sleeve surrounding a part of said bolt, substantially as described.

47. A composite end frame structure for railway cars, said structure comprising a plate metal bottom extended outward, in the direction of the length of the car, and in a plane different from the plane of the bottom, another metal plate member combined with the extended part of the bottom, a filling member located between said extension and said other plate member, a bolt extending through said plate members and said filling member, and a spacing sleeve surrounding a part of said bolt, substantially as described.

In testimony whereof I have signed my name, this 14th day of June, in the year one thousand nine hundred and twenty-four.

HUGH W. SANFORD.
